UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

PHASE-SPLITTING SYSTEM.

Application filed March 5, 1921. Serial No. 449,725.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Phase-Splitting Systems, of which the following is a specification.

My invention relates to alternating-current distributing systems and it has special relation to phase-splitting or modifying means whereby polyphase apparatus, such as motors and the like, may be operated from single-phase supply circuits.

In the prior art, as represented, for example, by my Patent No. 1,284,292, granted November 12, 1918, various phase-splitting devices of the static type embodying combinations of inductances and capacitances have been devised, but, in all cases, the necessary inductance values have been provided for the most part, by choke coils, or the like, that have been separate and distinct from other portions of the system, such as the main supply transformers.

One object of my invention, therefore, is to provide a phase-splitting system of the character set forth wherein the necessary inductance values are provided by or incorporated in novel main-transformer structures, whereby a double function is served by a portion of the apparatus and the expense of the system is materially decreased.

Viewed from another angle, the object of my invention is to provide, in a phase-splitting "bridge", or the equivalent, a plurality of inductive reactors that are influenced through the agency of inductive action in, or in connection with, the main supply transformer.

My invention may best be understood by reference to the accompanying drawings, wherein—

Figures 1, 2 and 3 are diagrammatic views of various forms of my present invention; and

Fig. 4 is a semi-diagrammatic view of a transformer structure which may be employed to advantage in connection with my invention.

Referring to Fig. 1, the system here shown comprises a main or supply transformer 1, which embodies a primary coil or winding 2 that may be energized from any suitable single-phase circuit, and a main secondary

winding or coil 3 that is adapted to supply electromotive force of the same phase relation as that of the single-phase supply circuit to one phase of the delivery circuit designated as phase "A". In addition, the transformer 1 embodies auxiliary secondary coils 5 and 7 of similar form, the winding 5 being loosely coupled with the primary winding 2, as conventionally indicated by the arrow 6, and the winding 7 being closely coupled with the primary winding 2.

A relatively small inductive reactor 8, external to the transformer 1, is connected in series relation with the loosely coupled winding 5, while a condenser 9 or other capacitance device is connected in series relation with the closely coupled winding 7. The junction of the reactor 8 and the condenser 9 forms one terminal of the second or quadrature phase "B" of the delivery circuit.

A relatively small inductive reactor 10 and a condenser or the like 11 are connected, external to the transformer 1, in series relation with the loosely coupled winding 5 on the opposite side of the winding from the reactor 8, and the "bridge" circuit is completed from the condenser 11 to the closely coupled winding 7. A point intermediate the winding 7 and the condenser 11 forms the other terminal of the quadrature phase "B".

In this way, by the provision of the coils 5 and 7 in the main transformer, the necessity of relatively large inductive reactors external to the transformer in the "bridge" circuit is obviated, and, furthermore, the customary adjustable core members for such external reactors are no longer required, since the desired adjustments may readily be made by providing a plurality of taps on either or both of the windings 5 and 7, as indicated by the arrows. Thus, a relatively simple and inexpensive phase-splitting system of the static type is provided.

Referring to Fig. 2, the supply conductors for phase "A", corresponding to the single-phase line voltage, are respectively connected to coils 16 and 19, which are cumulatively wound upon one leg of the main transformer core 18, the opposite or outer terminal of each of the windings 16 and 19 being connected to the respective conductors for the quadrature phase "B".

A plurality of coils 17 and 20 are oppositely wound around the same leg of the core 110

18 for providing the desired inductive effect in the phase-splitting "bridge." The coil 17 is connected in circuit with the primary coil 16 across the phase "B" and is adapted to act 5 cumulatively with respect to the coil 16. On the other hand, the coil 20, although connected in circuit with the coil 19 across phase "B," is adapted to act differentially with respect to the other three coils, as indicated by 10 the corresponding arrows.

A second leg of the transformer is provided with a winding or coil 21, across which a condenser 22 forming the condensive part 15 of the "bridge" is connected. In this way, the main transformer is employed to step-up the voltage to the condensive portion of the "bridge," and any desired variation in the value of this portion to maintain balanced polyphase operation in the phases "A" and 20 "B" may be obtained by changing the transformer winding taps of either the secondary winding 21 or of the primary coils 16 and 19, as indicated by the various corresponding arrows. The coils 17 and 20, constituting 25 the reactive parts of the phase-splitting "bridge," are wound on the same magnetic circuit as the other coils but are differentially connected so that they have no mutual inductance with respect to the condenser circuit embodying the coil 21.

In Fig. 3, a main supply transformer 25 is shown as embodying a primary winding 26 and a plurality of parallel-connected secondary windings 27 and 28. An auxiliary 30 transformer 31 is provided with a primary coil 32 which is connected to the mid-points 29 and 30 of the secondary windings 27 and 28 of the main transformer. A plurality of secondary windings 33 and 34 are provided 35 in the auxiliary transformer 31, and the corresponding terminals of these secondary windings are connected outside of the transformer by means of condensers, or the like, 40 35 and 36, respectively. Furthermore, the junction-point of the transformer coil 33 and the condenser 35 is connected to one common terminal of the secondary windings 27 and 28 of the main transformer 25, while the diagonally opposite point of the "bridge" 45 is connected by conductors 37 to the opposite terminal of the secondary windings.

Phase "A" is provided by connecting suitable conductors across the terminals of the 50 secondary windings 27 and 28 of the main transformer, whereas phase "B" is obtained by connecting suitable conductors to the junction-point of the auxiliary transformer coil 34 and the condenser 36.

By thus tapping the secondary windings 60 of the main transformer at their middle points and inductively connecting such points to the "bridge" circuits through the agency of the winding 32 and the coils 33 and 34 forming parts of the phase-splitting "bridge," the desired reactive effect from the

main transformer is transmitted to the circuits in question.

Desired variations in the value of the reactive portions of the "bridge" may be obtained by changing the number of turns in 7 the windings 32, 33 and 34, as indicated by the corresponding arrows.

Fig. 4 shows a transformer structure which may be employed to advantage in connection with certain portions of the previously described systems, wherein two groups of coils are so wound as to be in opposition, so far as the main flux is concerned.

The illustrated structure comprises a hollow rectangular transformer 40 having an intermediate cross-bar or leg 41, upon which is wound a plurality of oppositely disposed coils 42 and 43. If desired, a shunt magnetic path may be provided comprising magnetizable members or laminated bars 44 and 45 which are located in the center portions of the openings provided by the outer and the intermediate legs of the transformer.

The illustrated structure requires a relatively small amount of space and adds inappreciably to the cost of the main transformer. This structure, in general, is known in the art, since similar devices have been employed for sustaining inductance in rectifiers, etc.

The two coils 42 and 43 in Fig. 4, correspond, for example, to the oppositely-wound coils 19 and 20 in Fig. 2, or to the upper sections of the coils 27 and 28 or to the two parts of winding 27, for instance, in Fig. 3.

It will be seen that I have thus provided a phase-splitting "bridge" of the static type wherein the necessary inductance values are provided by, or are incorporated in, the main transformer.

I do not wish to be restricted to the specific circuit connections or arrangement of parts herein set forth, as various modifications thereof may be made without departing from the spirit and scope of my invention. I desire, therefore, that only such limitations shall be imposed as are indicated in the appended claims.

I claim as my invention:

1. A phase-converting system comprising a primary transformer winding, a main secondary winding for producing one phase of the converted system, a plurality of auxiliary secondary windings, and a plurality of capacitance devices connected in a closed circuit alternately with said auxiliary windings to produce a second phase of the converted system.

2. An electrical system comprising a primary transformer winding, a main secondary winding, a plurality of auxiliary secondary windings and a plurality of capacitance devices connected between the sets of terminals of said auxiliary windings, said auxiliary windings being loosely and closely

coupled, respectively, with said primary winding.

3. A phase-converting system comprising a primary transformer winding, a main secondary winding for producing one phase of the converted system, a plurality of auxiliary secondary windings, and a plurality of capacitance devices connected in a closed circuit alternately with said auxiliary windings to produce a second phase of the converted system, said auxiliary windings being loosely and closely coupled, respectively, with said primary winding. 40

4. The combination with a single-phase supply circuit, of a transformer associated therewith, phase-splitting means also embodying portions of said transformer, and means for varying the action of said means by varying the transformer portions embodied therein. 45

5. An electrical system comprising a primary transformer winding, a main secondary winding, a plurality of auxiliary secondary windings, a plurality of capacitance devices connected between the sets of terminals of said auxiliary windings, and means comprising movable tap-connections on said auxiliary windings for varying the inductance of the circuit thereof. 50

30 6. A phase-converting system comprising a primary transformer winding, a main secondary winding for producing one phase of the converted system, a plurality of auxiliary secondary windings, a plurality of capacitance devices connected in a closed circuit 55

alternately with said auxiliary windings to produce a second phase of the converted system, and a plurality of movable tap-connections associated with said auxiliary windings. 60

7. An electrical system comprising a primary transformer winding, a main secondary winding, a plurality of auxiliary secondary windings, a plurality of capacitance devices connected between the sets of terminals of said auxiliary windings, said auxiliary windings being loosely and closely coupled, respectively, with said primary winding, and means comprising movable tap-connections on said auxiliary windings 50 for varying the inductance of the circuit thereof. 65

8. A phase-converting system comprising a primary transformer winding, a main secondary winding for producing one phase of the converted system, a plurality of auxiliary secondary windings, a plurality of capacitance devices connected in a closed circuit alternately with said auxiliary windings to produce a second phase of the converted system, said auxiliary windings being loosely and closely coupled, respectively, with said primary winding, and a plurality of movable tap-connections associated with said auxiliary windings. 65

In testimony whereof, I have hereunto subscribed my name this 28th day of February, 1921.

CHARLES LE G. FORTESCUE.
